(57) **CLAIM**

The ornamental design for a shell deflector for upper receiver, as shown and described.

DESCRIPTION

FIG. 1 is a top front isometric view of the shell deflector for upper receiver of the present invention;

FIG. 2 is a top rear isometric view of the invention of FIG. 1;

FIG. 3 is a bottom front isometric view of the invention of FIG. 1;

FIG. 4 is a bottom rear isometric view of the invention of FIG. 1;

FIG. 5 is a left side elevation view of the invention of FIG. 1;

FIG. 6 is a top plan view of the invention of FIG. 1;

FIG. 7 is a bottom plan view of the invention of FIG. 1;

FIG. 8 is a front view of the invention of FIG. 1; and,

FIG. 9 is a rear view of the invention of FIG. 1.

The broken dash lines are for illustrative purposes only. Neither the portions outside of the broken dash lines nor the broken dash lines themselves forms any part of the claimed invention.
